UNITED STATES PATENT OFFICE

JOHN E. LOVELY, OF SPRINGFIELD, VERMONT, ASSIGNOR TO JONES & LAMSON MACHINE COMPANY, OF SPRINGFIELD, VERMONT, A CORPORATION OF VERMONT

WORK HOLDING MECHANISM

Application filed June 28, 1930. Serial No. 464,471.

This invention relates to mechanism for holding work for rotation with a spindle and has for an object to provide a mechanism by which the work may be grasped or released at will, the work when released being permitted to drop freely without substantial motion axially of the spindle. The work therefore may be clamped axially between relatively movable parts arranged coaxially of the spindle, and is centered for such clamping and is clamped by means movable axially of the spindle, which, when in work releasing position, is retracted axially of the spindle out of transverse alinement with the work. The work carried is provided with a central bore within which the work-engaging mechanism may engage, work such as tubular work being well adapted to be held by this mechanism.

For a more complete understanding of this invention, reference may be had to the accompanying drawings in which

Figure 1 is a fragmentary front elevation of a lathe embodying such a mechanism, the work being shown in position.

Figure 2 is a section to a larger scale substantially on line 2—2 of Figure 3.

Figure 3 is a section on line 3—3 of Figure 1.

Figure 4 is a view similar to a portion of Figure 2, but showing the work-released position of the parts.

Figure 5 is a section on line 5—5 of Figure 2.

Figure 6 is a section on line 6—6 of Figure 1.

Figure 7 is a view somewhat similar to Figure 6, but showing the tailstock plunger in elevation in work-released position.

Figure 8 is a view to a larger scale similar to a portion of Figure 6.

Figure 9 is a diagrammatic view of the fluid pressure motor actuating the headstock.

Figure 10 is a disassembled view of the headstock work centering and gripping mechanism.

Referring to Figure 1, at 1 is indicated the bed portion of a lathe having a headstock at 2 and a tailstock at 3. As shown in Figures 6, 7 and 8, the tailstock 3 has a tubular portion 5

within which is axially slidable a sleeve 6 having suitable bearings as at 7 and 8 to receive a tailstock spindle 9. This tailstock spindle is shown as provided with a tapered pilot portion 10 which is arranged to enter the opening in a hollow or tubular piece of work 12 to properly center one end as is shown in Figures 6 and 7. The sleeve 6 is mounted for axial movement within the tubular portion 5 and may be given such movement by means of a stem 15 connected to a piston member 16 operating in a fluid pressure cylinder 17 of usual construction. By admitting fluid under pressure, as through the pipe 18, the plunger 6 and the pilot 10 are retracted, the fluid pressure exhausting through the pipe 19. By admitting fluid under pressure through the pipe 19 and exhausting through the pipe 18, the sleeve 6 and the pilot 10 are moved in the opposite direction. This outward movement of the pilot 10 is employed to press the work 12 against a member on the headstock. This member, as shown best in Figures 2 and 4, is a tubular member 25 having a work-receiving and stop plate 26 on its forward end against which the work directly engages.

The tubular member 25, as shown, is provided with an annular flange 27 at its rear end by which it may be secured in any suitable manner to a spindle nose 28 of the lathe. As shown this securing means comprises bolts, one of which is indicated at 29, passing through the flange 27 and threaded into an opening 30 in the spindle nose. At 31 is shown a key piece secured to the nose 28, which rides in a depression in the flange 27, thus to key the nose and member 25 for simultaneous rotation. The member 25 and its stop plate portion 26, which are rigidly fixed together, as by means such as screws 32, are thus arranged in axial alinement with the lathe spindle 35.

Positioned within the member 25 is an element 40 slidably guided for axial movement therein and preferably prevented from turning relative to the member 25, as by means of the key 41 riding in a groove 42 in the element 40. The element 40 has a reduced diameter portion 44 extending between an

annular shoulder 45 at its inner end and the inner face of a locating or pilot head 46 at its outer end. This portion 44 is tapered with its small diameter end adjacent to the head 46. This head 46 acts as a pilot entering the opposite end of the hole in the work 12 from the tailstock pilot 10.

Arranged about the tapered portion 44 are segmental parts 50 having their inner 10 faces mating the taper of the portion 44, these parts being of less length than the portion 44 so that they may be moved axially thereof. When they are positioned adjacent to the head 46, their outer faces are in contracted 15 position, in which position they are free to enter the hole in the work 12 with the pilot portion 46, and they are normally held in this position, as by means of spring pressed plugs 51 seated in sockets 52 in the member 40. The 20 outer ends of the plugs 51 are flattened to engage in suitable slots 55 in the rear ends of the segmental parts 50. These segmental parts are thus held keyed against relative rotation with respect to the element 40. The 25 element 40 is shown as connected to an actuating rod 60, which as indicated diagrammatically in Figure 9, forms the piston rod of a fluid pressure motor having a cylinder 61. When fluid pressure is admitted to the outer 30 end of this cylinder, it is also admitted to the outer end of the cylinder 17 at the tailstock end of the machine. This causes the tailstock to be advanced toward the headstock, causing the pilot 10 to enter the hole 35 in the work and clamp the work against the member 26, while at the same time the member 40 is actuated to project its head end into the opposite end of the work and to carry therewith the outer ends of the segmental 40 members 50. This takes place until the further motion of the segmental parts 50 is stopped by reason of annular shoulders 62 thereon contacting with a mating shoulder 63 on the stop member 26. Continued movement 45 of the member 40 thus causes the larger diameter end of the portion 44 to pass between the segmental members, thus forcing them apart and into clamping engagement with the inner wall of the work opening.

50 When the air control valve 65 is manipulated to exhaust fluid pressure from the outer ends of the cylinders 17 and 61 and to admit fluid under pressure to the inner ends of these cylinders, the pilot portions are withdrawn, 55 the element 40 being retracted within its tubular housing portion, as shown in Figure 4, and the pilot 10 being retracted sufficiently to free the work from the end of the stop member 26, whereupon the work is free to 60 drop out from between the head and tailstocks. The headstock mechanism may, if desired however, be used without the tailstock.

65 From the foregoing description of an embodiment of this invention, it should be evi-

dent to those skilled in the art that various changes and modifications might be made without departing from the spirit or scope of this invention as defined by the appended claims.

70 I claim:

1. A mechanism of the class described comprising a tubular member having an end flange for attachment to a lathe spindle nose coaxially with said spindle, an element movable axially within said member to be retracted thereinto or to project from said member within an opening in work placed against said member, parts movable with said element for engagement with the wall of said opening, and a stop for limiting the projection of the parts to less than the full extent of projection of said element, said element and parts having cooperating portions causing further projecting movement of said element after said parts are stopped to press said parts outwardly into engagement with said wall.

75 2. A mechanism of the class described comprising a tubular member, means for attaching said member to a lathe spindle in axial alignment therewith, an element having a shoulder and slidably axially within said member and having a conical head at its outer end and a tapered portion back of said head, its small diameter portion being adjacent thereto, said tapered portion being positioned outwardly of said shoulder, parts arranged about said tapered portion having inner faces mating the taper thereof, said parts being of less length than said tapered portion, means for yieldingly holding said parts pressed about said head so that their outer faces are in contracted position, a tubular 80 stop for limiting the outward movement of said parts with said element, means for holding tubular hollow work against said stop with its opening positioned to receive said element, and means for projecting said element to cause its head to enter the work and center the same, and said parts to first enter the work and then to spread thereagainst as said element is projected further after said parts contact with said stop, and for retracting said element to first relieve the clamping 85 pressure of said parts thereagainst and then to withdraw said parts and element from the hole in the work.

90 3. A mechanism of the class described comprising oppositely disposed rotatable pilots for supporting and centering tubular work, means for moving said pilots toward and from each other to clamp and release work, a tubular stop for one of said pilots against which the work is held by the other of said pilots and into which said one pilot is retractable, and means actuatable when said pilots are moved to work-engaging relation for clamping one of said pilots against the inner 95 face of the work.

4. A lathe having head and tailstocks, a tubular member carried by said headstock in axial alignment therewith, means in said tubular member projectable to engage the inner wall of tubular work positioned thereagainst, fluid pressure means for projecting and retracting said engaging means, fluid pressure means for moving said tailstock toward said headstock to press the work against said member or away from said headstock to release the work, and a control device common to both of said fluid pressure means.
5. A mechanism of the class described, comprising a pair of oppositely disposed elements movable toward and from each other to clamp tubular work therebetween, one of said elements being tubular, and means retractable axially within said tubular element and projectable axially therefrom and outwardly into clamping engagement with the inner wall of the work.
6. A lathe having head and tailstocks, a tubular member carried by said headstock in axial alignment therewith, means in said tubular member projectable axially therefrom and outwardly to engage the inner wall of tubular work positioned thereagainst, means for projecting and retracting said engaging means, means for moving said tailstock toward said headstock to press the work against said member or away from said headstock to release the work, and a control device common to both said projecting and retracting and said tailstock-moving means.
7. A mechanism of the class described comprising a tubular member against an end of which work may be engaged, an expandable and contractable work engaging means movable axially within said tubular member, and means actuatable to project said work engaging means from said end and to retract said work engaging means into said member, said mechanism including means for expanding said work engaging means to engage the inner wall of hollow work engaging said end when said engaging means is so projected.
8. A mechanism of the class described comprising a tubular member against an end of which work may be engaged, an expandable and contractable work engaging means movable axially within said tubular member, and means actuatable to project said work engaging means from said end and to retract said work engaging means into said member, said projecting means including means acting on said work engaging means to expand it into engagement with the inner wall of hollow work engaging said end when said engaging means is so projected.
9. A mechanism of the class described comprising a tubular member against which the end of hollow work may be placed, work engaging means movable axially in said tubular member and retractable entirely within

said member, and means actuatable to project said engaging means beyond said end and outwardly into engagement with an internal face of the work.

In testimony whereof I have affixed my ¹⁰ signature.

JOHN E. LOVELY.
